Primary Examiner — Ruth McInroy(74) *Attorney, Agent, or Firm* — Thomas W. Galvani, P.C.; Thomas W. Galvani(57) **CLAIM**

The ornamental design for a swimming pool cleaner appendage, as shown and described.

DESCRIPTION

FIG. 1 is a top perspective view of a swimming pool cleaner appendage shown in accordance with my new design;

FIG. 2 is a bottom perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear elevation view thereof; and,

FIG. 8 is a front elevation view thereof.

The features shown in broken lines form no part of the claimed design.
